UNITED STATES PATENT OFFICE

136,404

DESIGN FOR A COMBINED COFFEE AND TEA MAKER

Frank E. Wolcott, West Hartford, Conn., assignor to The Silex Company, Hartford, Conn., a corporation of Connecticut

Application February 18, 1943, Serial No. 109,575

Term of patent 14 years

To all whom it may concern:

Be it known that I, Frank E. Wolcott, a citizen of the United States, residing at West Hartford, in the county of Hartford and State of Connecticut, have invented a new, original, and ornamental Design for a Combined Coffee and Tea Maker, of which the following is a specification, reference being had to the accompanying drawing, forming part thereof.

Fig. 1 is a side elevational view of a combined coffee and tea maker embodying my new design.

Fig. 2 is a fragmentary sectional view, taken on line 2-2 of Fig. 1 and in the direction of the arrows.

The dominant feature of my design resides in the portion illustrated in full lines in the drawing.

I claim:

The ornamental design for a combined coffee and tea maker, substantially as shown and described.

FRANK E. WOLCOTT.
